We claim the ornamental design for a television camera, as shown and described.

DESCRIPTION

FIG. 1 is a front perspective view of a television camera showing our new design;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a cross-sectional view taken along the line 9-9 in FIG. 3 with the internal parts being omitted; and,

FIG. 10 is a cross-sectional view taken along the line 10-10 in FIG. 6 with the internal parts being omitted.

The broken lines depict portions of the television camera in which the design is embodied that form no part of the claimed design. Additionally, the dash-dot lines denote the boundary of the claim and form no part of the claimed design.
